UNITED STATES PATENT OFFICE.

GEORGE M. LAUB, OF BROOKLYN, NEW YORK, ASSIGNOR TO EXCELLA PATTERN COMPANY, INC., OF NEW YORK, N. Y., A CORPORATION OF NEW YORK.

PATTERN AND METHOD OF AND MEANS FOR MAKING THE SAME.

Application filed May 11, 1922. Serial No. 560,073.

This invention relates to a pattern, and aims to provide an article of this character as well as a method whereby the same is to be constructed.

5 It is an object of the present invention to provide a pattern such as is used for example in the dress-making art, this pattern having associated with its body the instructions necessary for the proper use of the 10 same, so that it will be unnecessary to refer to a separate instruction sheet.

A further object of this invention is that of providing a device of the character stated which will present certain indicating marks, 15 the instructions afore-mentioned being preferably disposed in proximity to the said marks, so that the danger of error is reduced to a minimum.

A still further object of this invention 20 is that of furnishing a pattern which presents a cut outline corresponding to the shape of the piece of material which is to be produced, so that when the same is in use it will be unnecessary to trim the edge 25 of the pattern or to otherwise manipulate the same in order to shape the material to the desired outline.

Another object of the present invention is that of providing a device of the character 30 stated in which, as afore mentioned, indicating marks are preferably used, these marks being of such a character that it is unnecessary to slit the pattern to correspondingly mark the underlying material.

35 Still another object of the present invention is that of furnishing a pattern in which the necessary instructions and directions are directly incorporated, this being effected preferably by printing this data on the face 40 of the pattern by machine operation, whereby the expense of stamping the patterns by hand is avoided.

Other objects of the invention will in part be obvious and will in part appear herein- 45 after.

For a fuller understanding of the nature and objects of the invention reference should be had to the following detailed description taken in connection with the accompanying 50 drawing, in which:

Fig. 1 is a plan view of a pattern blank and showing the same prior to the outlining operation;

Fig. 2 is an enlarged fragmentary view

showing a master pattern applied to a portion of the pattern blank; and

Fig. 3 is a similarly enlarged plan view showing one of the finished patterns produced by means of the present invention.

In the present embodiment, the invention 60 has been shown as applied to a body garment pattern, and illustrates in detail the back section thereof.

Thus referring to Fig. 1, it will be seen that a pattern sheet has been shown, involving the various portions of the garment, this sheet being identified by the reference numeral 10, and embracing any suitable material, such as paper. It will further be noted in this view that no cut or printed outlines 70 of the various units have been disclosed, but it will be seen that the face of the sheet bears certain imprints, such as for example, a narrow 11 and blocks 12 and 12', the purpose of these marks being hereinafter brought 75 out. Furthermore, it will be seen that the face of the sheet 10 is divided into sections, and these sections may be identified as at 13 by a suitable designating phrase, code number and identification mark, etc. Key marks 80 14 and 14' also appear upon the face of the sheet 10 and are arranged adjacent certain of the boundaries of each of the sections 85 afore mentioned. Embraced within each of these sections are certain indicia, which provide directions for the use of the pattern and in the present instance these are in the nature of instruction phrases, as has been clearly shown in Fig. 1.

It is to be understood that prior to the preparation of the sheet 10 a master pattern is cut by an expert, and, as has been shown in Fig. 2, this pattern embraces a plurality of sections or complementary parts, only one of which is shown as at 16. In 95 order to incorporate indicating marks in the master pattern, it will be noted that in the present instance the same has been formed with suitable notches *a'*, *b'* and *c'* at proper points in its edges and has further 100 been provided by the pattern cutter with groups of perforations *d'* and *e'*. The area embraced by this pattern is carefully plotted and in the event that the sheet 10 as shown in Fig. 1 is prepared by a printing 105 press all of the type involving the instructions, identifications, etc., is carefully distributed within an area corresponding to the area

afore mentioned and it is to be noted, in this connection, that each master pattern such as 16 is preferably marked as at 11' with a direction indicator which may take 5 the form of an arrow and that this master part may bear upon its face identification marks 13' corresponding to the identification marks 13 upon the sheet 10 for a purpose hereinafter brought out. Finally, in the 10 present embodiment it will be noted that key marks 15 and 15' form a part of each master section and in printing the sheet 10, symbols are included to provide the key marks 14 and 14', which latter are to co- 15 operate with key marks 15 and 15' of the corresponding master pattern section.

It is obvious that a single pattern section may be printed during each operation of the press, or in the interest of economy and as 20 has been shown in the present exemplification, the printing is done so that a number of different pattern sections will appear upon each of the finished sheets 10, it being understood that as in usual procedure the 25 various sections are so correlated that a minimum amount of the sheet 10 will be wasted.

The press is now set in operation and on 30 each actuation of the same a sheet 10 is produced. These sheets may be stacked either automatically or by hand. In this connection it is of interest to note that the block 35 marks 12 and 12' serve to prevent any of the sheets being reversed, in that an operator may always refer to these marks in order to 40 properly arrange the sheets one upon another. When a suitable stack is produced it will be understood that corresponding pattern sections of each individual sheet are 45 disposed one above the other and the master pattern section 16 is now placed upon the uppermost of the sheets afore mentioned and more particularly over that portion of the same to which it corresponds.

50 This distribution of the master pattern sections is facilitated due to the fact that each of the same bears an identifying mark as 13' corresponding to the mark 13 identifying that section of the sheet 10 to which the master pattern, in question, is to be applied, and each master pattern also carries a direction indicator 11', which when matched with the direction indicator 11 of the sheet 55 10 will absolutely prevent any danger of error. In order to obtain perfect registration of the master pattern on the underlying pattern sheets, the key marks 15 and 15' are properly aligned with the key marks 14 and 14' respectively of the top sheet 10 of the 60 stack, as has been clearly brought out in Fig. 2.

The outline of the master pattern may now either be traced upon the uppermost sheet 10 in any suitable manner and the latter may be subsequently operated upon to

produce the finished pattern section, or a suitable cutting instrument may be caused to operate upon the stacked sheets 10 in such a manner that it accurately follows the outline of the master pattern, it being understood that a suitable punching or boring implement may be employed in order to form all of the stacked sheets with perforations *d* and *e* corresponding to the perforations *d'* and *e'* in the master pattern, while notches *a*, *b* and *c* corresponding to the notches *a'*, *b'* and *c'* in the master pattern may be formed by the cutting instrument or by a further suitable tool provided for this purpose. 70 75 80

Now upon the cut section of each of the sheets 10 being removed, it will be understood that a pattern such as has been shown in Fig. 3 is produced, and this pattern will correspond in all particulars to the master pattern and will present a cut outline, perforations and notches, and in addition this pattern will also present instructions upon its face which instructions are provided adjacent those portions of the pattern which are to be manipulated according to the directions afore mentioned. It will also be obvious in this connection that the instructions on underlying pattern sections may not be in absolute registry due to possible irregularities incident to stacking or cutting, but it will be appreciated that these instructions will be sufficiently near those portions of the pattern which are to be manipulated in accordance with the same, that the possibility of error occurring is reduced to a minimum. Most important, however, is the fact that each tissue pattern section is an accurate counterpart, in outline and dimension, of the corresponding master section, and each bears on its face the complete correlated instructive data for its use. It is to be particularly noted that the method of manufacture as set forth insures the result 90 95 100 105 110 stated and also permits its uniform accomplishment in large scale production.

It will also be noted that while the blanket sheet has printed thereon indicia applicable to a plurality of pattern sections, and symbols (key-marks) for registry with the master pattern sections, these symbols are so disposed both on the blanket sheet and on the master patterns that each of the latter is applicable to only the proper area of the blanket sheet. Furthermore, due to the differences between the key-marks and their disposition upon the master patterns and blanket sheets, it will be obvious that each master pattern may only be applied in a proper manner to that area of the 125 blanket sheet which it is to cover.

Thus all the objects of this invention are accomplished, and since certain changes in carrying out the above method, and certain modifications in the article which embody 130

the invention may be made without departing from its scope, it is intended that all matter contained in the above description or shown in the accompanying drawings 5 shall be interpreted as illustrative and not in a limiting sense.

It is also to be understood that the following claims are intended to cover all of the generic and specific features of the invention 10 herein described, and all statements of the scope of the invention which, as a matter of language, might be said to fall therebetween.

Having described my invention, what I 15 claim as new and desire to secure by Letters Patent, is:

1. A method of manufacturing tissue paper patterns, which consists in providing a series of printed instructions and keymarks upon sheets of severable material and in 20 stacking together a number of such sheets, and in subsequently outlining each of said sheets to provide a finished pattern section having its edge corresponding to the actual outline of the garment portion to be formed, 25 the pattern section thus provided having the instructions appearing upon its body, the keymarks being on said sheet but beyond the outline of said body.

2. A method of making a pattern which 30 includes the provision of a master pattern presenting indicating marks, the subsequent preparation of a sheet of material bearing indicia interpretative of such marks, and the outlining from said sheet of a pattern corresponding to the outline of said master pattern and bearing said indicia.

3. A method of making a pattern which includes the provision of a master pattern presenting key marks, and the use of a sheet 40 of material from which the finished pattern is to be formed, said sheet also presenting key marks, the marks borne by the different elements being adapted to be brought into registry one with the other to properly correlate said elements, the keymarks on said sheet extending beyond the area covered by said master pattern.

4. A method of making a tissue paper pattern which consists in the provision of a 50 master pattern presenting key marks, the stacking of a plurality of tissue paper sheets, the uppermost of which also carries key marks, and the subsequent application of said master pattern to said uppermost sheet 55 to assist in the outlining of said sheets, said master pattern and sheets being properly correlated by bringing the key marks into registry with each other.

5. In combination, a master pattern and a 60 sheet of tissue paper having printed key marks between which said master pattern is adapted to be disposed, said master pattern also having key marks adapted to be brought into registry with said first named key

marks, whereby to properly correlate said 65 master pattern with said sheet.

6. In combination, a master pattern having an outline and a sheet having indicia corresponding to said outline and means for correlating said pattern and sheet, so that 70 the outline of the pattern will correspond with the indicia on the sheet.

7. In pattern manufacture, in combination, a blanket tissue sheet having printed indicia thereon applicable to a plurality of 75 pattern sections and a master pattern to be superposed on said sheet to control the severance of the latter into separated pattern sections, said sheet and said master pattern having complementary symbols to permit 80 registry of the latter on the former only in predetermined relationship.

8. The method of making tissue paper patterns, which includes imprinting a plurality of blanket sheets with informative 85 data, stacking said sheets in approximate registry, and severing said stacked sheets into a plurality of stacks of separate pattern sections, each pattern section of its respective stack having exactly registering cut 90 margins to be followed in cutting a corresponding garment section, and having its printed data in only approximate registry with respect to said margins.

9. The method of manufacturing tissue 95 paper patterns, which includes imprinting a plurality of blanket sheets with instructive data arranged in correlated groups, said sheets being substantially free of printed indications of the shapes and dimensions 100 of the pattern sections to be formed, stacking said sheets in approximate registry, applying to the top sheet of the stack means to indicate the shape and dimension of the respective separate pattern sections, and finally, cutting said stacked sheets along the 105 lines of the indicated shapes and dimensions of the separate pattern sections of said top sheet.

10. The method of manufacturing tissue 110 paper patterns, which includes imprinting a plurality of blanket sheets with data to identify a plurality of separate pattern sections and to instruct regarding the use thereof, stacking said sheets, applying to the uppermost sheet of said stack means to indicate the shape and dimension of the respective pattern sections, and finally, cutting said stacked sheets along the lines of the indicated shapes and dimensions of the sections 115 to provide pattern sections, each having their cut edges defining the edge of the garment section which is to be formed thereby.

11. As an article of manufacture, a tissue 120 paper blanket sheet from which a number of pattern sections are to be formed, said sheet being provided with data printed upon its face, said data being correlated and ar-

ranged in groups, each group being so disposed upon said sheet as to fall within the area of a pattern section, said sheet being substantially free of outlines of said pattern sections.

12. The method of making tissue paper patterns, which includes the provision of a master pattern having indicating marks, such as notches and openings, imprinting a plurality of tissue paper blanket sheets with data interpretive of said indicating marks, stacking said sheets in approximate registry, applying the master pattern to the uppermost sheet of the stack to define the dimensions and shape of the section which is to correspond to the master pattern, and thereafter cutting said stacked sheets along the lines defined by said master pattern and incorporating in the sections thus produced the indicating marks associated with said master pattern.

13. The method of manufacturing dress patterns and the like, which comprises imprinting on predetermined portions of a sheet of severable material, one or more sets of printed directions and one or more key marks associated with each of said sets of printed directions, applying to each of said sets of printed directions a master pattern having a key or keys corresponding to the key or keys of the particular set of printed directions and of such dimensions as to include within its outline the particular set of printed directions, and thereafter cutting the pattern section out of the sheet of severable material by tracing with a cutter the outline of the master pattern.

In testimony whereof, I have signed my name to this specification this 6th day of May, 1922.

GEORGE M. LAUB.
